UNITED STATES PATENT OFFICE.

THOMAS S. HARLAN, OF SALT LAKE CITY, UTAH.

SANITARY DENTAL WASTE-RECEPTACLE.

1,022,316.

Specification of Letters Patent.

Patented Apr. 2, 1912.

Application filed June 19, 1909. Serial No. 503,079.

To all whom it may concern:

Be it known that I, THOMAS S. HARLAN, a citizen of the United States of America, and resident of Salt Lake City, Salt Lake county, Utah, have invented a certain new and useful Improvement in Sanitary Dental Waste-Receptacles, of which the following is a specification.

My invention contemplates an improved receptacle for use by dentists, consisting of a removable cup and holder for the same, the said cup holder being provided with a swiveled support adapted to be fastened to the under side of a cabinet or table, whereby the receptacle can be swung out of sight beneath the cabinet or table, as will hereinafter more fully appear.

In the accompanying drawings—Figure 1 is a perspective of a sanitary dental waste receptacle, embodying the principles of my invention, showing the same attached to the under side of the corner of a dental cabinet. Fig. 2 is an enlarged plan view of the receptacle shown in Fig. 1. Fig. 3 is a vertical sectional view on line 3—3 in Fig. 2.

As thus illustrated, my invention comprises an L-shaped arm A provided at its upper end with a reduced end portion a and at its lower and right hand end with an upstanding threaded portion a'. A bracket bearing B is provided with holes b, whereby the same can be attached to the under side of the cabinet X, said bracket bearing being also provided with a vertical bore or opening b' adapted to receive the stem a of the arm. The top of the bracket bearing B has a depression or seat b², in which is disposed a washer b³, the upper end of the stem a being riveted over to hold the said washer thereon. In this way a swivel connection is provided between the arm A and the bracket bearing B, whereby the arm is adapted to revolve about a vertical axis. The cup C is provided with annular side walls, and with a bead or rib c extending circumferentially thereof, located some distance above the bottom thereof. An annular cup-holder D is also provided, the perimeter d thereof being rounded and curled over to provide edges d' that engage immediately below the bead or rib c, as shown. Thus the cup is supported by contact therewith at some distance above its bottom or lower edge, and does not contact with the bottom of the cup-holder. The said cup-holder is provided with a centrally disposed and downwardly projecting boss d²

provided with a threaded bore or opening adapted to receive the threaded stud a' on the swinging or swiveled arm. In this way the cup is removable from the cup-holder, and the cup-holder is removable from the L-shaped swiveled arm by which it is carried. As a matter of further and special improvement, the said cup may have a portion of the interior thereof provided with a series of teeth E, disposed near the perimeter or upper edge of the cup, whereby cotton or waste may be readily dislodged from the dental instrument. By placing the instrument between two of the teeth, and then drawing the instrument upward, the cotton or waste or other material on the lower end of the instrument will be completely dislodged or removed therefrom.

From the foregoing, it will be seen that the advantages of my invention are as follows: It is sanitary, because it can be emptied and sterilized after each patient, or at any time, without consuming more than a moment's time. The contents are out of sight of the patient at all times, and the swinging arm enables the operator to swing the cup under the corner of the table, so that the next patient taking the chair cannot see into the cup; then when the patient is seated, and the operator pulls the table up to the patient, the cup may be pulled out, and the operator has full access to the cup without the patient having seen the contents thereof. It holds any and all waste from the dental table. The receptacle proper, being cup-shaped, holds any and all waste, such as old burs, disks, polishing strips, ligatures, carborundum, stones, articulating paper, all sized cotton pellets and the cotton rolls which are being used more every day, and any size that is used in the mouth can be put in this receptacle, and much other waste from the dental chair. The receptacle, being fastened to the nearest right hand corner of the table, enables the operator to dispose of waste with the least loss of time; and should heavy oils or coagulations of blood cause cotton to hang to the pliers, the operator can do this by drawing the pliers to the right until the cotton comes in contact with a set of spurs or teeth fastened near the top and on the inside with points curved downward where it will be impossible for the cotton to pass over or through the spurs. It is not in the way of the operator, as by taking up valuable

space on the table. The receptacle, being placed underneath the table, is out of the way, and occupies space that can be used for nothing else, leaving the table for instruments or other things necessary for the work.

The receptacle, being made of steel or copper, heavily nickelated and nicely ornamented, is quite an ornament to any dental table. Being made of heavy steel or copper, and being heavily nickelated, the device should last a lifetime, and the cup cannot be knocked out of its position unless taken hold of and lifted straight up. The shank of the receptacle is fastened to the frame of the table by two screws which securely fasten it, and the receptacle proper can be turned around easily without jarring the table or loosening anything, as it fits in a socket. The sides of the cup-holder bulge outwardly beyond the cup, thus guarding the latter against contact with other objects that might cause its dislodgment, or tends to do so.

Although I have described my invention as being particularly useful in connection with dental work, it will be understood that I do not so limit myself, and that it may be used for various purposes without in any way departing from the spirit of my invention.

What I claim as my invention is:

1. A sanitary dental waste receptacle comprising an L-shaped arm provided with a

swivel at its upper end, an annular cup-³⁵
holder disposed upon the lower end of said arm, and a cup removably disposed in said cup-holder, the latter having an annular perimeter engaging the sides of the cup at a distance above the bottom thereof. ⁴⁰

2. In a device of the character disclosed, an L-shaped arm, a swivel for the upper end of said arm, adapted to be attached to the under side of a support, a cup-holder on the lower end of the arm, and a cup removably disposed in said cup-holder, the latter being formed with an annular perimeter, and with sides bulging outwardly beyond the perimeter of the said cup. ⁴⁵

3. In a device of the character disclosed, an L-shaped arm, a swivel for the upper end of said arm, adapted to be attached to the under side of a support, a cup-holder for the lower end of said arm, and a cup removably disposed in said cup-holder, said cup provided with an annular bead or rib located at a distance above the bottom thereof, and the said cup-holder being provided with an annular and inwardly projecting edge or perimeter adapted to engage the cup immediately below said bead or rib, as set forth. ⁵⁰

Signed by me at Salt Lake City, Utah,
this 14th day of June, 1909.

THOMAS S. HARLAN.
